UNITED STATES PATENT OFFICE

152,711

DESIGN FOR A BOOK-HOLDING LAMP

Martha Michaelson Lund, Chicago, Ill.

Application May 31, 1946, Serial No. 130,248

Term of patent 7 years

(Cl. D48—20)

To all whom it may concern:

Be it known that I, Martha Michaelson Lund, a citizen of the United States and resident of Chicago, in the county of Cook and State of Illinois, have invented a new, original, and ornamental Design for a Book-Holding Lamp, of which the following is a specification, reference being had to the accompanying drawing forming a part thereof.

The drawing is a perspective view of a book holding lamp showing my new design. A perspective view taken from a point diagonally opposite the present one would have the same appearance.

I claim:

The ornamental design for a book-holding lamp, as shown and described.

MARTHA MICHAELSON LUND.
